UNITED STATES PATENT OFFICE.

OSWALD TROVA, OF ST. LOUIS, MISSOURI, ASSIGNOR, BY DIRECT AND MESNE ASSIGNMENTS, OF ONE-HALF TO KING BEE SPARK PLUG COMPANY, OF ST. LOUIS, MISSOURI, A CORPORATION OF MISSOURI, AND ONE-HALF TO FREDERICK J. REPPENHAGEN AND JOHN E. CURLEY, OF ST. LOUIS, MISSOURI.

SPARK-PLUG.

1,384,413.

Specification of Letters Patent. Patented July 12, 1921.

Application filed February 9, 1920. Serial No. 357,275.

To all whom it may concern:

Be it known that I, OSWALD TROVA, a citizen of the United States, residing at St. Louis, Missouri, have invented a certain new and useful Improvement in Spark-Plugs, of which the following is a full, clear, and exact description, such as will enable others skilled in the art to which it appertains to make and use the same, reference being had to the accompanying drawings, forming part of this specification.

My invention relates generally to spark plugs, and more particularly to a plug having current carrying members or electrodes that are spaced apart a slight distance to produce a gap that is effective in intensifying the spark that is produced between the electrodes at the lower or inner end of the plug.

The principal objects of my invention are, to generally improve upon and to simplify the construction of the existing types of spark plugs that have intensifying spark gaps; and to provide a relatively simple and efficient construction that is, under all conditions, self-adjusting in the formation of an intensifying gap, thereby wholly eliminating all manual operations and adjustments necessary to produce an effective intensifying gap.

Further objects of my invention are, to provide an intensifying gap spark plug which may be easily and cheaply produced, capable of being readily assembled or taken apart; and to provide a plug having an air-tight chamber in which the automatically adjustable intensifying gap is located.

With the foregoing and other objects in view, my invention consists in certain novel features of construction and arrangement of parts, hereinafter more fully described and claimed, and illustrated in the accompanying drawings, in which—

Figure 1 is a vertical section taken through the center of a spark plug of my improved construction.

Fig. 2 is an enlarged vertical section taken through the center of the means utilized for producing the self-adjusting intensifying gap.

Fig. 3 is a horizontal section taken on the line 3—3 of Fig. 2.

Referring by numerals to the accompany-

ing drawings which illustrate a practical embodiment of my invention, 10 designates the main body portion of the plug, the same being in the form of a substantially cylindrical shell of metal, the lower portion of which is externally threaded as designated by 11 so as to be inserted into the wall of an internal combustion engine. The upper portion of this shell 10 is preferably enlarged and provided with an internal thread which receives the externally threaded lower portion of a metal bushing 12.

Inasmuch as the upper portion of the shell 10 is larger than the lower portion, an internal inclined shoulder 13 is formed between the upper and lower portions of said shell and resting upon this shoulder is a gasket 14 of metal or a combination of metal and asbestos and the like. Resting upon this gasket 14 is the underface of an annular flange 15 that projects outwardly from the central portion of a core 16 of suitable insulating material such as porcelain and through which passes a current carrying member or electrode 17. The lower portion of this electrode projects a short distance below the lower end of core 16 and terminates adjacent to the inner end of a radially arranged electrode 18, the latter being secured to the lower end of shell 10.

The upper end of the core 16 terminates in a rounded upwardly presented lug 19, and the upper end of the electrode 17 projects a slight distance above the top of this lug.

Interposed between the lower end of the bushing 12 and the upper face of the annular flange 15 on core 16 is a gasket 20 and when bushing 12 is screwed tightly into the shell 10 this bushing forms an air tight joint between the core 16 and said bushing.

Fitting snugly within the upper portion of the bushing and secured thereto in any suitable manner, preferably by cement, is a cap insulator 21 of porcelain or analogous material, in the lower portion of which is formed an upwardly extending recess 22. Axially disposed in the upper portion of this cap insulator is a substantially cylindrical member 23 of metal in which is formed an upwardly projecting recess 24.

Formed integral with and projecting upwardly from member 23 is a threaded stem

25 and positioned thereupon is a nut 26 and a washer 27, and which parts are effective in anchoring member 23 in the cap insulator. The upper end of the threaded stem 25 receives the usual terminal receiving nut 28.

Arranged to slide freely in the recess 24 is a short cylindrical stem 29, and formed integral with the lower end thereof is an inverted cup-shaped member 30, the rounded 10 lower inner edge 31 of which bears upon the rounded upper face of lug 19, and the space within the chamber 32 between the upper end of electrode 17 and the adjacent surface of the inverted cup-shaped member 30 15 forms the intensifying gap which must be crossed by the current in its passage to the electrode 17.

I have demonstrated in practice that to achieve best results in a device of this kind, 20 the width of this intensifying gap should be approximately one-thirty-second of an inch, although, of course, this width may vary according to the size of the plug or to the voltage of current utilized in connection 25 with the ignition system.

Positioned on stem 29 and interposed between the cap 30 and the lower end of member 23 is a relatively light compression spring 33 which acts to hold the rounded 30 lower edge 31 of the cap against the rounded top of plug 19.

To retain the stem 29 in sliding engagement with member 23, the upper portion of stem 29 is provided with an annular groove 35 34 of considerable width and projecting into said groove from the wall of member 23 are lugs 35.

It frequently happens that through imperfect manufacture or distortion while 40 baking, the core insulators 16 are not always uniform in size and shape and as a result, it is practically impossible to produce the desired and effective spark gap by manual adjustment of parts, but in my improved 45 construction, the spring-pressed member 29 has considerable vertical movement and while the bushing 12 carrying cap insulator and parts associated therewith is screwed into the upper end of shell 10, the cap 30 50 carried by the lower end of member 29 will engage the lug 19 on the upper end of core insulator 16 and automatically adjust itself so as to form the desired and effective intensifying gap. The inverted cup-shaped 55 member 30 cooperates with lug 19 in forming, under all conditions, a universal joint, and which arrangement is effective in producing without manual manipulation or adjustments, the desired intensifying gap.

60 My improved spark plug can be easily and cheaply manufactured, and the automatic adjustment between the current carrying parts provides an intensifying gap which is constant under all conditions. This 65 gap is effective in intensifying firing spark

produced between the lower end of the electrode 17 and the radial electrode 18, and as a result, said firing spark is relatively strong and hot or of such degree as to insure ignition of the explosive charges in the combustion chambers of the engine. 70

After my improved plug has been in operation for a short time, the greater portion of the nitrogen and oxygen in the air within chamber 22 will be consumed by the spark produced at the intensifying gap within said chamber and as a result of this absence of atmospheric resistance, the efficiency of the device in operation is materially increased. 75

It will be readily understood that minor changes in the size, form and construction of the various parts of my improved spark plug can be made and substituted for those herein shown and described, without departing from the spirit of my invention, the scope of which is set forth in the appended claims. 80

I claim:

1. In a spark plug, a shell, an insulating core positioned therein, an electrode extending through said core, a cap insulator inclosing the upper portion of said insulating core, and a self adjusting electrode carried by said cap insulator and adapted to bear upon the upper portion of the insulating core whereby an intensifying spark gap is formed between said self-adjusting electrode and the electrode that extends through said core. 90

2. In a spark plug, a shell, an insulating core positioned therein, an electrode extending through and projecting beyond the upper end of said core, a cap insulator inclosing the upper portion of said insulating core and the projecting terminal of the electrode extending therethrough, and a spring-pressed electrode carried by said cap insulator and adapted to bear upon the upper portion of the insulating core around said projecting end of said electrode, whereby a spark gap is formed between said spring-pressed electrode and the electrode which extends through said core. 100

3. In a spark plug, a pair of electrodes, means for maintaining said electrodes in spaced relation to form an intensifying gap, and a spring associated with one of said electrodes and tending to normally force it toward the other electrode. 115

4. In a spark plug, a pair of electrodes, means for maintaining said electrodes in spaced relation to form an intensifying gap, and a spring associated with one of said electrodes and tending to normally force it toward the other electrode, the end of said spring-pressed electrode partially inclosing the adjacent end of the other electrode. 125

5. In a spark plug, a pair of spaced electrodes, one of which is spring-pressed to 130

ward the other, and means for maintaining said electrodes in spaced relation.

6. In a spark plug, a pair of spaced electrodes, one of which is spring-pressed toward the other, and provided with a recess which receives the adjacent end of the opposite electrode, and means for maintaining said electrodes in proper spaced relation.

7. In a spark plug, a shell, a core insulator positioned therein, a bushing removably connected to said shell, a cap insulator carried by said bushing, there being an air-tight chamber formed between the core insulator, the bushing, and the cap insulator, electrodes carried by the core and cap insulators, the adjacent ends of which electrodes terminate within the air-tight chamber, means for maintaining said electrodes in spaced relation, and a portion of one of said electrodes being spring-pressed toward the other.

8. In a spark plug, a shell, a core insulator positioned therein, a bushing removably connected to said shell, a cap insulator carried by said bushing, there being an air-tight chamber formed between the core insulator, the bushing, and the cap insulator, electrodes carried by the core and cap insulators, the adjacent ends of which electrodes terminate within the air-tight chamber, means for maintaining said elec-

trodes in spaced relation, and a portion of one of said electrodes being spring-pressed toward the other and provided with a recess for the accommodation of the projecting end of the other electrode.

9. In a spark plug, a shell, a core insulator positioned therein, a bushing removably seated in the shell, a cap insulator carried by said bushing, an electrode passing through the core insulator, an electrode passing through the cap insulator, a portion of which last mentioned electrode is spring-pressed and normally bears on the upper portion of the core insulator to maintain the electrodes in spaced relation and form an intensifying spark gap.

10. In a spark plug, a pair of insulators, electrodes passing therethrough, and a spring-pressed member forming a part of one of said electrodes, the end of which spring-pressed member bears on the end of the insulator carrying the opposite electrode to maintain the electrodes in spaced relation and thereby form an intensifying spark gap and the terminal portion of said spring-pressed member partially surrounding the projecting end of the end portion of the opposite electrode.

In testimony whereof I hereunto affix my signature this 3d day of February, 1920.

OSWALD TROVA.
